ATTORNEY.

UNITED STATES PATENT OFFICE.

WALTER C. CARTER, OF PITTSBURGH, PENNSYLVANIA.

DESIGN FOR A GAME-BOARD.

58,069.

Specification for Design.

Patented June 7, 1921.

Application filed October 11, 1920. Serial No. 416,333. Term of patent 7 years.

To all whom it may concern:

Be it known that I, WALTER C. CARTER, a citizen of the United States, residing at Pittsburgh, in the county of Allegheny and State of Pennsylvania, have invented a new, original, and ornamental Design for a Game-Board, of which the following is a specification, reference being had to the accompanying drawing, forming part thereof.

The figure is a face view of a game board showing my new design.

I claim:

The ornamental design for a game board, as shown.

WALTER C. CARTER.
